ABSTRACT OF THE DISCLOSURE

Fire-resisting doors consist of an incombustible material or are at least combined therewith and have, at the edges and/or in the door frame rabbet, layers of materials which expand under heat and which in the case of fire, fill out the gap between the edge of the door and the door frame with foamlke substances which offer certain resistance to the spread of fire at these particularly endangered places.

The present invention relates to the provision of such expandable materials along the edges of the door.

The edges and corners of fire-resisting closures, for example fire-resisting doors, are particularly weak spots through which flames and smoke first penetrate. Fire-resisting wooden doors first burn through at these spots, so that the unexposed face of the door ignites although the door itself is still substantially intact and would offer adequate resistance. This problem occurs particularly on the hinge side of the fire-resisting doors. These problems are not so serious when the fire breaks out on the side of the door away from the hinge because the edges of the door are substantially protected by the door frame.

To overcome this disadvantage it is known that grooved depressions may be provided along the edges of the door and/or in the door frame and that they may be filled with an expandable material. This material consists substantially of an organic binder, for example polyvinyl acetate, and an expanding agent which disengages gas when heated, for example dicyanodiimide or ammonium phosphate. When subjected to high temperatures, such as occur when a fire breaks out, this material expands between the edge of the door and the door frame. The foam thus formed has only slight mechanical stability however and consequently offers only limited resistance to the spread of the fire. Another disadvantage is that the expandable material introduced into the grooves cannot be covered to protect it from mechanical damage because otherwise it would not expand sufficiently and above all not quickly enough in the event of fire.

It is also known that articles may be protected from the effects of a fire by means of alkali metal silicate especially sodium and potassium silicate sheets which contain water and glass fibers. These sheets have the property, owing to the high temperature to which they are subjected in the event of fire, of expanding to a foamed layer which has very good mechanical and thermal stability.

These alkali metal silicate sheets have, with reference to the anhydrous alkali metal silicate contained therein, a water content of 20 to 70% by weight, preferably 40 to 60% by weight, and fibers in an amount of 10 to 40% by weight, preferably 15 to 25% by weight. Glass fibers are stated to be particularly suitable fibers, and especially fibers having a thickness of from about 0.1 to 0.3 cm. are favorable which consist of many individual filaments

whose diameter is from 5 to 15 microns. These fibers are known as chopped strands.

We have now found that the fire resistance of fire-resisting doors is considerably improved by providing, along the edges and/or in the door frame rabbet, strips which consist of at least one layer of alkali metal silicate containing fibers and water and a material having good thermal conductivity, said strips being arranged with their narrower side perpendicular to the face of the door.

Fire-resisting doors whose edges or door frame rabbet have been provided only with strips of alkali metal silicates containing fibers and water have greater fire resistance as compared with doors whose edges have been provided with organic compounds which expand when heated. Surprisingly however this resistance may be considerably increased by combining the strips containing alkali metal silicate with strips of a material having good thermal conductivity. This measure of combining the alkali silicate strips with a material having good thermal conductivity would have led one to expect exactly the opposite effect, namely that the fire resistance of a fire-resisting door would be reduced.

In the event of fire, the alkali metal silicate strips containing fibers and water form a mechanically stable foam which fills out the frame and the door so that the door becomes firmly jammed in the frame. Penetration of heat, flames and smoke is thus prevented even when the fire continues for a prolonged period. In the case of wooden doors there is less warping. Doors even remain in their frames when, as a result of the stiles charring, the hinges are no longer anchored in the door.

The strips containing alkali metal silicate and the strips of material having good thermal conductivity have a width which advantageously is about equal to the width of the edge of the door. The thickness of the strips containing the alkali metal silicate is advantageously about 1.5 to 2.5 mm. The thickness of the material having good thermal conductivity depends on the thermal conductivity of the particular material chosen. For example in the case of materials having good thermal conductivity such as copper and aluminum, the latter being particularly suitable, thicknesses of 0.1 to 0.3 mm. are sufficient, whereas with materials having poorer thermal conductivity, e.g. iron, correspondingly greater thicknesses must be used. By materials having good thermal conductivity we mean those which have a high heat transfer coefficient of at least 0.09 cal./cm.×sec.×°C., which are thermally stable and whose melting point is above 500° C. The strips are advantageously arranged along the edge of the door in such a way that first there is a strip containing alkali metal silicate and then a strip of material having good thermal conductivity. On these strips, for example, another strip containing alkali metal silicate may be laid. It is also possible to place a metal strip on either side of the strip containing the alkali metal silicate. Such a combination reacts particularly quickly under the action of fire. This combination of strips may be covered with protective layers, for example of wood veneer, bonded asbestos sheets or plastics without the effect being lost. Obviously it is also possible to use layers consisting of more than three strips instead of layers consisting of only three strips. The fire retarding effect is thus further enhanced at the corners and edges. The number of layers chosen depends therefore on the fire-retarding effect to be achieved.

In order to ensure increased resistance to the passage of heat and flame at the corners of the door, which constitute a particularly weak spot, it is advantageous to chamfer the corners and to apply a plurality of layers of strips containing alkali metal silicate and strips of a thermally conducting material in such a way that the

chamfer is filled up with these strips and the foam expands in the direction of the corner.

The invention will be further described with reference to the accompanying drawings in which FIGURE 1 is a horizontal section and FIGURE 2 is a vertical section of a door. FIGURE 3 is a horizontal section of a door, a door frame and the adjacent brickwork. The same parts are indicated by the same reference numerals in all the figures.

In FIGURE 1, 1 indicates a face veneer and 2 indicates the facing which advantageously consists of an incombustible, thermally insulating material, for example a sheet of alkali metal silicate containing fibers and water. 3 and 3a indicate the fire-resisting edging member consisting of strips of alkali metal silicate containing fibers and water and strips of material having good thermal conductivity. 4 indicates an outer layer, for example of hardwood, asbestos cement sheets or plastics. 5 indicates the framework of the door, for example of glued strips. 6 indicates the panel. As more clearly shown in FIGURE 2, the corners of the stiles of the door are chamfered and the chamfer is filled up with a plurality of layers of strips of alkali metal silicate containing fibers and water 3 alternating with strips of material having good thermal conductivity, for example aluminum foil, 3a.

In FIGURE 3, 7 indicates brickwork and 8 a door frame of steel or wood. 9 indicates the door. A strip 3 of alkali metal silicate containing fibers and water and a metal foil 3a are applied to the door frame 8, the metal foil being covered with a protective layer 10.

The invention is further illustrated by the following examples.

EXAMPLE 1

The door has a total thickness of 54 mm., a height of 1,990 mm. and a width of 986 mm. The framework, which is 35 mm. thick and consists of three spruce strips, each 30 mm. in width, glued together, is provided with a twice glued lock reinforcement and a horizontal rail. The frame and the hardboard connecting members are covered on both sides with the following layers:

On a veneer having a thickness of 1.5 mm. there is a sheet 1.5 mm. in thickness of sodium silicate having a water content of 30% by weight and a ratio of $\text{Na}_2\text{O}:\text{SiO}_2$ of 1:1.3. 0.5 mm. gauge wire cloth with a mesh of 25 mm. is embedded in the sheet. It also contains 120 g./sq. m. of chopped glass strands and 50 g./sq. m. of cane sugar. The sheet is coated on either side with 100 g./sq. m. of an epoxide resin. This sheet is followed by another wood veneer having a thickness of 1.5 mm. and then again by a sodium silicate sheet. The final layer is a cross-grained wood veneer 1.5 mm. thick. The whole five layers are firmly glued together with a phenol-resorcinol-formaldehyde condensation resin at a temperature of 100° C. This covering is glued onto the framework of the door and further secured with twenty penetrating steel clips, 55 mm. in width. The four corners of the framework of the door are chamfered so that both edges are shortened by 40 mm. The chamfer is filled up by alternate layers of fourteen strips about 1.5 mm. in thickness of sodium silicate containing fibers and water and thirteen strips of aluminum foil having a thickness of 0.1 mm.

The edges of the door are provided all round with a fire-resisting edging member about 50 mm. in width. This member, viewed in the direction of the door, of a wood veneer 0.8 mm. thick, a sodium silicate strip 1.5 mm. thick whose composition is like that of the above-mentioned sheet and which is coated on both sides with epoxide resin, an aluminum foil having a thickness of 0.1 mm., another strip of sodium silicate and another wood veneer having a thickness of 0.8 mm. To this fire-resisting edging member, at the sides and bottom, a 5 mm. edging member of oak is applied and an edging member of asbestos cement is applied to the top of the

door. Each of the two side faces are covered with a cross-grained veneer 0.8 mm. thick.

This door is provided with a lock and hinges and flush mounted in a frame of sheet steel.

In a fire test by exposing the hinge side of the door to flame, the following results are obtained depending on the temperature in the fire chamber and on the duration of the test:

10	Duration in minutes	Temperature in fire chamber (° C.)	
30-----	880	The door is firmly jammed in the frame.	
60-----	1,000	No change.	
90-----	1,025	End of test, a small hole has formed at the upper left-hand corner.	

EXAMPLE 2

Two doors, each having a total thickness of 40 mm. are constructed, as described in Example 1, from wooden strips having a thickness of 30 mm., hardboard members and wood veneer faces 1.5 mm. thick, a sheet of sodium silicate 1.5 mm. thick and as defined in Example 1, and a wooden veneer 1.5 mm. thick.

(a) A fire-resisting edging member of a strip of sodium silicate 1.5 mm. thick is applied to the edges of one door. The upper chamfered corner of the door is filled up with fourteen superposed sodium silicate strips.

(b) A fire-resisting edging member of a strip of sodium silicate 1.5 mm. thick and an aluminum foil 0.1 mm. thick is applied to the edges of the other door. The similarly chamfered corner of this door is filled up with alternately superposed layers of fourteen sodium silicate strips and thirteen strips of 0.1 mm. aluminum foil.

An edging member of oak which has been rebated 10 mm. wide and 27 mm. deep, is applied to the fire-resisting edging members in both cases.

The two doors are fitted into commercial steel frames in an oven. In a fire test carried out according to DIN 4102 (1940) the following results are obtained by exposing the hinge side of the doors to the flames:

After the test has proceeded about twenty-five minutes, a hole appears at each of the upper corners of door (a), whereas this is not observed in the case of door (b) until after about forty minutes.

We claim:

1. A fire-resisting doorway comprising a door frame and a door therein, and at least one of the edge portions of said door and the door frame having mounted thereon superposed strips of (a) at least one layer of alkali metal silicate containing fibers and water and (b) at least one strip of a thermally stable, heat conductive material having a heat transfer coefficient of at least 0.09 cal./cm.× sec.× ° C. and a melting point above 500° to provide a heat expandable combination adapted to fill the gap between the edges of the door and the door frame in cases of fire, the strips being arranged with their narrower side perpendicular to the face of the door.

2. A fire-resisting door with its door frame-opposing edge portions having superposed strips of (a) at least one layer of alkali metal silicate containing fibers and water and (b) at least one strip of a thermally stable, heat conductive material having a heat transfer coefficient of at least 0.09 cal. cm./× sec.× ° C. and a melting point above 500° C. to provide a heat expandable combination adapted to fill the gap between the edges of the door and the door frame in cases of fire, the strips being arranged with their narrower side perpendicular to the face of the door.

3. A fire-resisting door comprising a door body having at least one chamfered corner which is filled out by a plurality of diagonally disposed, alternate strips of heat foammable alkali metal silicate containing fibers and water and strips of thermally stable, heat conductive material having a heat transfer coefficient of at least 0.09 cal./cm.× sec.× ° C. and a melting point above 500° C., the strips

being arranged with their narrower side perpendicular to the face of the door.

4. A fire-resisting door frame having a door frame rabbet and characterized by said rabbet having superposed strips of (a) at least one layer of alkali metal silicate containing fibers and water and (b) at least one strip of a thermally stable, heat conductive material having a heat transfer coefficient of at least 0.09 cal./cm. $\times$ sec. $\times$ °C. and a melting point above 500° C. to provide a heat expandable combination adapted to fill the gap between the edges of the door and the door frame in cases of fire, the strips being arranged with their narrower side perpendicular to the face of the door.

5. A fire-resisting doorway as claimed in claim 1 wherein the layers of said alkali metal silicate have a thickness of 1.5 to 2.5 mm.

6. A fire-resisting door as claimed in claim 2 wherein the layers of said alkali metal silicate have a thickness of 1.5 to 2.5 mm.

7. A fire-resisting door frame as claimed in claim 4 wherein the layers of said alkali metal silicate have a thickness of 1.5 to 2.5 mm.

8. A fire-resisting doorway as claimed in claim 1

wherein said heat conductive material is copper foil, aluminum foil, or a thin iron strip.

9. A fire-resisting door as claimed in claim 3 wherein said heat conductive material is copper foil, aluminum foil, or a thin iron strip.

10. A fire-resisting door frame as claimed in claim 4 wherein said heat conductive material is copper foil, aluminum foil, or a thin iron strip.
